United States Patent Office

Des. 198,240
Patented May 19, 1964

198,240

VIEWER-PRINTER OR THE LIKE

Joseph H. Wally, Jr., Shawnee Mission, Kans., assignor to
Western Blue Print Company, Kansas City, Mo., a cor-
poration of Missouri

Filed Dec. 3, 1962, Ser. No. 72,699

Term of patent 14 years

(Cl. D61—1)

Fig. 2

Fig. 3

FIGURE 1 is a front perspective view of a viewer-printer or the like showing my new design;

FIGURE 2 is a side elevational view thereof taken from the side opposite that visible in FIGURE 1; and

FIGURE 3 is a top plan view thereof.

The rear of the viewer-printer or the like, not shown, is plain and unornamented.

I claim:

The ornamental design for a viewer-printer or the like, substantially as shown and described.
